(57) **CLAIM**

The ornamental design for a nail polish remover bottle, as shown and described.

DESCRIPTION

FIG. 1 is a perspective view of of a design for a nail polish remover bottle, showing my new design.

FIG. 2 is a perspective view of the nail polish remover bottle of FIG. 1 shown without the cap.

FIG. 3 is a front elevational view of the nail polish remover bottle of FIG. 2.

FIG. 4 is a rear elevational view of the nail polish remover bottle of FIG. 2.

FIG. 5 is a left elevational view of the nail polish remover bottle of FIG. 2.

FIG. 6 is a right elevational view of the nail polish remover bottle of FIG. 2; and,

FIG. 7 is a top elevational view of the nail polish remover bottle of FIG. 2.

The broken lines in the drawings illustrate a portion of the nail polish remover bottle which form no part of the claimed design.
